Primary Examiner — Paula Greene*(74) Attorney, Agent, or Firm* — NSIP Law(57) **CLAIM**

We claim the ornamental design for a neck support for headset, as shown and described.

DESCRIPTION

FIG. 1 is a front perspective view of a neck support for headset showing our new design;

FIG. 2 is a rear view thereof;

FIG. 3 is a front view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view thereof in which the headset is shown in an alternate position.

The broken line showing of the headset is for environmental purposes only and forms no part of the claimed design.
